UNITED STATES PATENT OFFICE.

JAMES T. COWLEY, OF BOSTON, MASSACHUSETTS, ASSIGNOR TO THE LAMSON COMPANY,
OF NEWARK, NEW JERSEY, A CORPORATION OF NEW JERSEY.

PNEUMATIC AMMUNITION-CONVEYING APPARATUS.

1,148,078.

Specification of Letters Patent. Patented July 27, 1915.

Application filed February 25, 1908. Serial No. 417,772.

To all whom it may concern:

Be it known that I, JAMES T. COWLEY,
of Boston, in the county of Suffolk and State
of Massachusetts, have invented certain new
5 and useful Improvements in Pneumatic Am-
munition-Conveying Apparatus, of which
the following is a specification.

My invention relates to improvements in pneumatic ammunition conveying apparatus and its object is to provide means for the rapid, safe and efficient conveying of ammunition from the handling room or the magazine to the guns.

15 Means are provided for electrically controlling at the gun the despatching and conveying of the ammunition, and said means are operative to prevent the admission of air pressure to drive the load until the load has been inserted at the despatching station and the despatch station closed.

At the gun or receiving station is provided an inclosed receptacle which is adapted to receive and cushion the delivery of the ammunition and which is provided with a suitable cover that may be opened to remove the charge and which normally prevents the accidental firing of the charge.

accidental firing of the charge.

An air outlet is provided which permits the escape of air from the tube while a charge is in transit and which automatically closes when the charge has arrived in the receptacle, sealing the system and rendering the same fireproof.

At the despatching station a valve is utilized adapted to be operated from the receiving station to admit air for driving the charge and which is adjusted to automatically close when sufficient air has been admitted to insure the delivery of the charge.

40 In the accompanying drawings is illustrated a form of construction embodying my invention, in which,—Figure 1 is a diagrammatic view of the system. Fig. 2 is a sectional view of the air pressure controlling valve in normal or closed position. Fig. 3 is a side elevation of a portion of the receiving receptacle. Fig. 4 is a cross sectional view on line 4—4 Fig. 3. Fig. 5 is a longitudinal section of the receiving receptacle. Fig. 6 is a detail side view of the despatching end of the conveyer partly in section. Fig. 7 is a detail plan of the same with the conveyer removed.

Like letters of reference refer to like parts throughout the several views.

The handling room or sending station 1 adjacent the magazine is connected by a pneumatic conveyer 4 with the turret or receiving station 2. The conveyer 4 extends through the well 3 between the turret 2 and the handling room 1 and which well is sealed by a partition 3^a at its lower end, the conveyer 4 being provided with a swivel joint 4^a which permits of the rotation of the turret. 60 65

5 represents a despaching shelf adapted to support the ammunition previous to its insertion into the conveyer 4 and 39 is a pivoted gate or valve adapted to be operated by the handle 39^a to allow the insertion of the charge into the conveyer 4 and prevent the escape of the air for driving said charge. 70

9 is a pressure reservoir connected with an air compressor by a pipe 10, said reservoir being connected with the conveyer 4 adjacent valve 39 by a pipe 7, the admission of the air pressure to said conveyer 4 being controlled by the mechanism shown in Fig. 2 which will be hereinafter described. 75

8 represents a valve casing interposed in the air supply pipe 7 and which carries mounted therein the balanced valve 11 normally held in the position shown in Fig. 2 by means of spring 12, cutting off communication between passages 16 and 17 in pipe 7. The valve 11 has a central recess in which is mounted a slide valve 13, the outer end of which acts as the armature or core of solenoid magnet 15. 80 85

18 is a port adapted to connect passage 16 through passage 13^a and a port 19 with chamber 20 to admit air pressure to said chamber 20 when the valve or core 13 is actuated by magnet 15. The valve or core 13 is normally held in position shown in Fig. 2 by a spring 14, cutting off the admission of air pressure to chamber 20. The magnet 15 is in circuit with a normally open switch 45 located at the receiving station or turret 2 and source of electric supply α , through conductors b , a , c , a normally open automatic switch 41 located in the despatching end of the conveyer 4 and through conductor d and a normally closed switch 40, adapted to be operated by valve 39, and conductor c . The switch 41 comprises a trip pivoted at 42 and normally held projecting into the conveyer 4 by a spring 43. This trip is adapted to be engaged by the ammunition to close contacts 44-49. The switch 105

40 is pivoted at 46 and carries an arm 47 normally engaging a projection 48 on valve 39 which holds the same in a closed position as shown in Figs. 1 and 6.

5 50 is a spring connected to open said switch when the valve 39 is open.

6 is a receptacle located in the receiving station or turret 2 for receiving the ammunition, and 21 is an air outlet controlled by

10 the valve 22 pivoted at 23 normally held closed by the weight 24 when there is no ammunition in transit. The end of the receptacle 6 forms a cylinder or air chamber in which is mounted the piston 35 on rod 36; 15 said piston being normally held in dotted position shown in Fig. 1 by spring 37 and collar 36^a pinned to said rod 36 at 36^b. This forms a cushion for receiving the impact of the charge, the escape of the chamber 34 being regulated by a valve 38.

20 The bend in the conveyer 4, by which the movement of the ammunition is turned from vertical to horizontal for delivery to the horizontal receiver, acts to retard the ammunition and aids in securing its delivery gently and without shock. This retarding and cushioning of the ammunition, together with a closing of the air admission when sufficient air has been admitted to insure the delivery of the charge, as elsewhere described, assure the proper and safe delivery of the ammunition with a rapid operation of the apparatus.

25 The receptacle 6 has an aperture 33 for removing charge, said aperture being normally closed by a cover 25 adapted to be locked closed. Mounted on each side of the cover 25 are segmental hinges 26^a and 27^a which normally rest respectively on the 30 hinge rods 26 and 27 which are secured to the opposite sides of receptacle 6 by suitable fastenings 52. Pivoted at opposite sides of the cover 25 at 29 and 32 are the hand latches 28 and 31 respectively, the lower 35 ends of which complete the hinge and serve also to normally lock the cover 25 closed by action of springs 30.

40 The operation is as follows: The operator in the handling room opens the valve 39 by 45 means of the handle 39^a and pushes the ammunition P from the shelf 5 into the mouth of the conveyer 4 and closes said valve 39. The closing of this valve 39 closes the switch 40 and the ammunition resting on the trip 45 or switch 41 holds said switch closed this 50 completing the circuit through the magnet 15 with the exception of the open switch 45 in the turret 2. The gunner when ready for the charge closes the switch 45 completing 55 the circuit and energizing the solenoid magnet 15 which moves the valve or core 13 against the tension of the spring 14 until the passage 16 is placed in communication with the chamber 20 through port 18, passage 13^a and port 19 admitting air pressure

5 to said chamber 20 forcing the valve 11 against the spring 12 until passages 16 and 17 communicate admitting air pressure from reservoir 9 through the pipe 7 to the conveyer 4 and driving the charge P through 70 said conveyer to the turret 2. The air in the conveyer ahead of the charge opens the valve 22 against the action of the weight 24 and is expelled through the outlet 21.

75 When the charge moves forward from the mouth of the conveyer tube, the switch 41 is released and the circuit to the magnet is thereby opened at that point, deenergizing the magnet 15 and allowing the valve 13 to be returned to its normal position by the 80 spring 14. When the pressure in the receiver 9 has diminished sufficiently to permit the spring 12 to restore the valve 11 to normal position, the valve 11 is returned to the position shown in Fig. 2, cutting off 85 the supply of air to the conveyer 4. As previously stated, the valve is adjusted to close when sufficient air has been admitted to insure the delivery of the charge, the drop in pressure to that which is necessary to insure the delivery of the charge aiding materially in securing the proper and safe delivery of the charge, by avoiding high speed and shock at the delivery end, which would result if the full driving pressure were 90 maintained throughout the transmission of the charge. This delivery of the charge gently and without shock is aided also by the bend at the delivery end of the conveyer, 95 which acts to retard the movement of the charge, and all shock is avoided and the desired result is assured by the cushioning of the charge as it is delivered into the receptacle by spring 37 acting on piston 35, which the charge strikes, and by the slight escape 100 of the air in chamber 34 through the regulating valve 38, this valve 38 enabling the air cushioning to be adjusted accurately to 105 secure the desired cushioning effect.

110 The charge P may be removed from either side of the receptacle 6 by operating the hand latch on the desired side; for example, the latch 28 which releases that side of the cover 25. The opposite latch 31 remaining locked forms a complete hinge permitting the cover 25 to be swung open and the charge removed. After the charge is removed, the cover is allowed to close and be locked by the latch 28 thereby preventing 115 the possibility of fire entering the receptacle. It is preferable that a charge P remain in the mouth of the conveyer 4 ready to be transmitted when the gunner desires, but if the operator in the handling room should be in the act of inserting a charge 120 the air could not be admitted to the conveyer by closing the switch 45 in the turret. When the charge has been inserted closing the switch 41 and the valve 39 entirely shut, closing the switch 40, the circuit may be 125 130

completed by closing the switch 45 and admitting the air pressure to the conveyer for transmitting the charge. If there should be no charge in the mouth of the conveyer, the switch 41 would be open and the switch 45 could not then control the circuit, thereby preventing the exhausting of the pressure in the reservoir.

Having thus described the nature of my invention and set forth a construction embodying the same, what I claim as new and desire to secure by Letters Patent of the United States is:

1. In a pneumatic ammunition conveying apparatus, a conveyer, means for permitting ammunition to be inserted into the conveyer, means for supplying air under pressure to the conveyer behind ammunition which has been placed therein, and means located at the delivery end of the conveyer and controlled by the operator at said delivery end for electrically controlling the admission of air to the conveyer at the despatching end thereof for causing the ammunition to be driven to the delivery end thereof.

2. In a pneumatic ammunition conveying apparatus, a normally sealed conveyer normally under atmospheric pressure, means for permitting ammunition to be inserted into the conveyer, means for supplying air under pressure to the conveyer behind ammunition which has been placed therein, means for controlling the admission of air to the conveyer, a normally sealed receptacle at the delivery end, into which the conveyer opens and which is adapted to receive the ammunition, and normally closed means opened by the transit of ammunition to permit the escape of air from the conveyer and receptacle while the ammunition is in transit.

3. In a pneumatic ammunition conveying apparatus, a conveyer, a despatching station, a receiving station, the receiving station being movable relatively to the despatching station, and means for permitting the delivery end of the conveyer to move relatively to the despatching end as the receiving station is moved relatively to the despatching station.

4. In a pneumatic ammunition conveying apparatus, a conveyer, an air reservoir of determined capacity connected with the conveyer for supplying air under pressure to the conveyer behind ammunition which has been placed therein, said reservoir containing an initial charge of compressed air insufficient of itself to drive a charge of ammunition through the conveyer to the delivery end but having additional air supplied thereto while said ammunition is in course of transit, means for controlling the passage of air from said reservoir to the conveyer, and means for supplying said additional compressed air to said reservoir,

said last mentioned means being incapable of supplying sufficient air to transmit said ammunition at substantially uniform speed to the point of delivery of said ammunition and said additional air supplying means and reservoir being proportioned to each other and to said conveyer and coacting with said air controlling means to reduce the speed of the ammunition as it approaches delivery by decreasing the effective air pressure during the transmission of said ammunition.

5. In a pneumatic ammunition conveyer, a conveyer, a source of air pressure connected with said conveyer, a despatching station, a receiving station, means for controlling said source of air pressure by the operator at said receiving station for conveying ammunition through said conveyer, and means for preventing the admission of air pressure to said conveyer when no ammunition has been inserted into said conveyer for transmission.

6. In a pneumatic ammunition conveyer, a conveyer, a source of air pressure connected with said conveyer, a despatching station, a receiving station, means for controlling said source of air pressure by the operator at said receiving station for conveying ammunition through said conveyer, a valve or gate located at said despatching station and adapted to be opened to permit the insertion of ammunition into said conveyer, and means for preventing the admission of air pressure before said valve is closed.

7. In a pneumatic ammunition conveying apparatus, a conveyer, a despatching station, a receiving station, means for supplying air under pressure to the conveyer behind ammunition which has been placed therein, means for controlling from the receiving station the admission of air to the conveyer, a valve or gate at the despatching end of the conveyer adapted to be opened to permit the insertion of ammunition into the conveyer, and means for preventing the admission of air to the conveyer except when said gate is closed and ammunition is in position ready for transmission.

8. In a pneumatic ammunition conveying apparatus, a conveyer, a despatching station, a receiving station, means for supplying air under pressure to the conveyer behind ammunition which has been placed therein, electrically operated means for causing air to be admitted to the conveyer, a circuit to said electrically operated means and a plurality of circuit closing devices in said circuit, all of which must be closed in order to close the circuit, one of said circuit closing devices being operative from the receiving station and another of said circuit closing devices being automatically opened

when there is no ammunition in position ready for transmission.

9. In a pneumatic ammunition conveying apparatus, a conveyer, a despatching station, a receiving station, means for supplying air under pressure to the conveyer behind ammunition which has been placed therein, a valve or gate at the despatching end of the conveyer adapted to be opened to permit the insertion of ammunition into the conveyer, electrically operated means for causing air to be admitted to the conveyer, a circuit to said electrically operated means, and a plurality of circuit closing devices in said circuit, all of which must be closed in order to close the circuit, one of said circuit closing devices being operative from the receiving station and another of said circuit closing devices being automatically opened when said gate is opened and closed when said gate is closed.

10. In a pneumatic ammunition conveying apparatus, a conveyer, a despatching station, a receiving station, means for supplying air under pressure to the conveyer behind ammunition which has been placed therein, electrically operated means for causing air to be admitted to the conveyer, a circuit to said electrically operated means, a circuit closing device in said circuit operative from the receiving station, and means for preventing the completing of said circuit except when ammunition is in position ready for transmission.

- 35 11. In a pneumatic ammunition conveying apparatus, a normally sealed conveyer normally under atmospheric pressure, a despatching station, a receiving station, means for supplying air under pressure to the conveyer behind ammunition placed in the conveyer at the despatching station, and a valve at the receiving station opened automatically by the transit of ammunition to permit the escape of air from the conveyer while the ammunition is in transit and closing automatically to seal the conveyer when the ammunition has been delivered to the receiving station.

12. A pneumatic conveying apparatus comprising a vertical conveyer leading up from the ammunition chamber, a despatch station, a receiving station, an air supply for driving charges of ammunition through said conveyer, a bend in the conveyer at the receiving station for changing the movement of the ammunition from vertical to horizontal and acting to retard the movement of the ammunition, a substantially horizontal receiver, and means at said receiving station for causing the despatch of ammunition from the despatching station, the operation of said means being controlled by the position of parts at the despatching station.

13. In a pneumatic ammunition conveying apparatus, a conveyer, a despatching

station, a receiving station, an air supply for driving ammunition through the conveyer, air controlling devices at the despatching station, controlled by the operator at the receiving station and means for preventing the admission of air until a charge of ammunition has been inserted in the conveyer.

14. In a pneumatic ammunition conveying apparatus, a conveyer, a despatching station, a receiving station, an air supply for driving ammunition through the conveyer, air controlling devices at the despatching station, controlled by the operator at the receiving station and means for preventing the admission of air until a charge of ammunition has been inserted in the conveyer and the despatching station closed.

15. In a pneumatic ammunition conveying apparatus, a conveyer, a despatching station, a receiving station, an air supply for driving ammunition through the conveyer, a receiver for the ammunition at the receiving station, and devices at the receiving station for causing the despatch of ammunition from the despatching station to said receiving station, the operation of said devices being controlled by the position of parts at the despatching station.

16. In a pneumatic ammunition conveying apparatus, a conveyer, a despatching station, a receiving station, means for supplying air under pressure to the conveyer behind ammunition placed in the conveyer at the despatching station, a normally sealed receptacle at the receiving station normally under atmospheric pressure and to which the conveyer delivers, and a valve in the receptacle opening automatically to permit the escape of air from the receptacle ahead of the ammunition and closing automatically to seal the receptacle when the ammunition has been received.

17. In a pneumatic ammunition conveying apparatus, a conveyer, a despatching station, a receiving station, an air supply for driving ammunition through the conveyer, and electrical devices for causing the despatch of ammunition by the operator at the receiving station.

18. In a pneumatic ammunition conveying apparatus, a conveyer, a despatching station, a receiving station, an air supply for driving ammunition through the conveyer, electrical devices for causing the despatch of ammunition by the operator at the receiving station, and circuit connections at the receiving station and at the despatching station, both of which must be in proper position for the despatch of ammunition.

19. In a pneumatic ammunition conveying apparatus, a conveyer, a despatching station, a receiving station, an air supply for driving ammunition through the con-

veyer, electrical devices for causing the despatch of ammunition by the operator at the receiving station, and circuit connections at the despatching station preventing 5 the despatch of ammunition when the despatching station is open.

20. In a pneumatic ammunition conveying apparatus, a conveyer, a despatching station, a receiving station, an air supply 10 for driving ammunition through said conveyer, a main air admission valve, an auxiliary valve at the despatching station controlling said main admission valve, and means for controlling said auxiliary valve 15 from the receiving station to operate the main valve.

21. In a pneumatic ammunition conveying apparatus, a despatching station, a receiving station, a transmission tube extending 20 between said stations, a source of fluid supply for driving ammunition through the transmission tube from the despatching station to the receiving station, and a connec- 35

tion permitting the receiving station and delivery end of the tube to rotate without 25 disconnecting the transmitting tube.

22. In a pneumatic ammunition conveying apparatus, a despatching station, a receiving station, a transmission tube extending between said stations, a source of fluid 30 supply for driving ammunition through the transmission tube from the despatching station to the receiving station, and a connection between the delivery end of the transmission tube and the despatching station 35 permitting the delivery end to move with the receiving station relatively to the despatching station.

In testimony whereof, I have signed my name to this specification in the presence of 40 two subscribing witnesses, this twenty fourth day of February A. D. 1908.
